REGLET AND COUNTER-FLASHING

Edward T. Berg, San Francisco, Calif.

Application January 22, 1957, Serial No. 635,231

1 Claim. (Cl. 108—26)

The present invention relates to counter-flashings, such as are used in the construction of roofs to prevent seepage of water along vertical or inclined walls into the space underneath roofing materials that partially cover these walls. To hold counter-flashings in their proper position, it is necessary to build retaining channels, known as "reglets" into the walls during the construction thereof or to secure such channels to the finished walls.

It is an object of my invention to provide a reglet and counter-flashing combination that is effective in use, yet inexpensive and of the simplest construction.

Another object of my invention is to provide a reglet and counter-flashing combination that is of such construction that it may readily be installed around corners.

In particular, it is an object of the invention to provide a reglet and appertaining counter-flashing which are of such construction that they may readily be installed around corners without need to fit separate sections thereof together.

Furthermore, it is an object of my invention to provide a simple, effective and time-saving method of installing reglets and counter-flashings about corners, without need of cutting them into sections of appropriate size and fitting these sections together.

These and other objects of the present invention will be apparent from the following description of the accompanying drawing which illustrates a preferred embodiment thereof and wherein—

Figure 1 is a vertical section through a parapet wall provided with a reglet and counter-flashing embodying my invention;

Figure 2 is a fragmentary perspective of a blank for a counter-flashing embodying my invention;

Figure 3 is a fragmentary perspective of a blank for a reglet embodying my invention;

Figures 4 and 5 are fragmentary perspectives of the counter-flashing and the reglet, respectively, resulting from the blanks shown in Figures 2 and 3; and

Figure 6 is a fragmentary perspective of a completed installation of a reglet and counter-flashing embodying my invention.

In Figure 1 the reference numeral 10 indicates a parapet wall on a roof 12 that is covered with layers of a suitable roofing material 14 which is bent upwardly and bears with its upwardly bent portion 15 against the inner face 16 of the parapet wall. To prevent moisture from seeping into the space between the inner face of the wall and the roofing material, a counter-flashing 18 is held over the edge portion of the roofing material by a reglet 20 that is secured to the parapet wall above the edge of the roofing material.

The reglet 20 is made of a suitable sheet material, such as sheets of galvanized copper or steel, and it has an upper portion 26 of L-shaped contour which is intended to form a compartment 28 with the face 16 of wall 10. It also has a support portion 30 in the form of a vertically disposed bar that lies flat against the face of wall 10 and is suitably secured to said wall, such as by means of

2

nails or screws shown at 32 in Figure 1. The portion 34 of the upper part 26 of the reglet which corresponds to the long bar of the L and which forms one of the side walls of compartment 28, extends parallel to the support portion 30 and hence to the face 16 of wall 10, when the reglet is secured to the wall, and it has a straight horizontally disposed upper edge 36, over which is engaged a backwardly turned flange or lip 38 formed along the upper end portion of the counter-flashing 18 to suspend the counter-flashing in its proper position. The arrangement is such that the lip or flange 38 extends parallel to and lies closely adjacent to the main part or apron 40 of the counter-flashing which is formed by a planar vertically disposed sheet with no bends or curvatures. Along its lower edge said apron may be provided with another backwardly turned lip or flange 42 that is intended to bear against the upwardly bent end portion 15 of the layers of roofing material, and which is of the same conformation as the upper flange 38 lying parallel and closely adjacent to the apron or main body 40 of the counter-flashing 18.

Formerly, when reglets were applied to walls forming corners, it was necessary to cut them into sections of appropriate length corresponding to the straight areas of

25 the wall, and to secure them separately to these areas, which is a cumbersome and costly operation. Due to the simple construction of my novel reglet, as above described, and the parallel disposition of its portions 30 and

30 34, it is possible to install the reglet around corners in a continuous piece without need to cut it into separate sections of appropriate length. Having reference to Figures 3 and 5, I use a reglet blank of appropriate length,

and I mark on its support portion 30 the lines along which

the blank has to be bent to conform to the particular configuration of the wall to which it is to be applied, as indicated at 43 and 44 in Figure 3. Then, wherever the blank is to be bent to fit around a projecting corner, I

provide a simple straight cut or incision 45 in its wall portion 34 and the portion 46 corresponding to the short horizontal bar of its L-shaped contour. This may be done by any craftsman of average ability with the aid of a hack saw or like instrument. Where the reglet is to fit into a "concave" corner or recess, however, I remove a broad slice from the wall portion 34 of the reglet as

45 shown at 48 in Figure 3 and cut a converging notch 49 into portion 46. I then bend the blank along the bend lines 43 and 44 into the shape illustrated in Figure 5 to

50 conform with the wall to which it is to be applied, hold it against the wall in its proper position and secure it to the wall by means of screws or nails 32 as previously described (Figure 1).

It remains now to install the counter-flashing and to suspend it in its appropriate position from the reglet. As in the case of the reglet, it was formerly necessary to

55 cut the counter-flashing into appropriate sections corresponding to the straight areas of the wall and to fit these sections together in a water tight manner, such as by mitering, whereupon the composite structure was aligned with the wall and suspended from the reglet. To cut the

60 counter-flashing into sections of exactly predetermined length and to join the sections together at the proper angles is a time-consuming and cumbersome task which greatly increases the cost of the installation and which impairs the effectiveness and dependability of the resultant

65 composite structure because the joints of the counter-flashing sections may not be fluid tight, or may become defective and pass moisture on to the end portion of the roofing material underneath after a relatively short period of practical use.

70 In accordance with my invention, I bend a piece of counter-flashing of the proper length in a manner conforming to the configuration of the wall to which it is

to be applied. This is possible because the counter-flashing of the invention is made almost entirely of a flat sheet without bend and curvatures, as explained hereinbefore, and requires for suspension from the reglet nothing but the above-described backwardly turned straight flange 38 along its upper edge.

When preparing the counter-flashing for installation I mark upon the exposed face of its suspension flange 38 the places where it is to be bent outwardly or inwardly to conform with the configuration of the wall. Where the counter-flashing is to be turned outwardly to conform with a concave corner or recess, I provide a simple vertically extending straight incision in the flange 38 as shown at 50 in Figure 2, and where it is to be turned inwardly to fit around a projecting corner, I provide a straight vertically extending incision 52 of substantial width, lest the edges of the incision strike against each other and obstruct further bending during the subsequent bending operation. If the lower edge of the counter-flashing is provided with a flange or lip 42, as shown in Figures 1, 2 and 4, I provide incisions 50' and 52' in places in vertical alignment with the incisions 50 and 52 in the upper flange 38, as shown in Figure 2. I then bend the counter-flashing into the required shape along vertical bend lines 54 and 56 determined by the incisions 50, 50' and 52, 52' respectively, as illustrated in Figure 4.

After I have bent the counter-flashing in the described manner, I fit it against the reglet 20, drop its flange 38 over the upper edge 36 of the reglet structure and press it down into position until the bight portion of flange 38 bears against the straight upper edge 36 of the reglet structure, and its lower flange 42 bears against the upturned part 15 of the roofing material 14 (Figures 1 and 6). The counter-flashing may now be secured in its proper position by means of screws 53 that are engaged in aligned apertures 54 and 56 provided in the upper edge portion of its apron 40 and its flange 38 and in apertures 58 that may be punched into the intermediate wall portion 30 of the reglet as shown in Figure 1. With the counter-flashing properly engaged over the edge 36 of reglet 20 and secured in position by the screws, a suitable moisture-excluding compound is packed into the compartment 28 between the outer face of wall 10 and the flange 38 of counter-flashing 18, which can readily be done since the compartment is open at the top. Above compartment 28 the compound is preferably banked into a slope that slants upwardly toward and into contact with the wall 10 as shown at 60 in Figure 1.

The resultant installation is dependably water-tight

since the counter-flashing is a continual piece of metal sheet without joint or seam that might become defective (Figure 6), and since the installation of reglet and counter-flashing in accordance with my invention does not require that either the reglet or the counter-flashing be cut into sections which have to be fitted together in their proper relative positions, the method of installing reglets and counter-flashes in accordance with my invention saves a very substantial part of the time and labor that was formerly necessary for the installation of reglets and counter-flashes on walls of irregular configuration.

While I have explained my invention with the aid of a particular embodiment thereof, it will be understood that the invention is not limited to the specific constructional details shown and described which may be departed from, without departing from the scope and spirit of my invention.

I claim:

20 A flashing installation for walls forming corners comprising a reglet of sheet metal having a support portion adapted to lie flat against the wall and a wall portion disposed parallel to and above said support portion in a different vertical plane and having a straight horizontally disposed upper edge, said wall portion having vertical incisions at points corresponding to the corners in said wall and said reglet being bent to conform to the configuration of the wall along vertical lines determined by said incisions, a continual counter-flashing formed by a metal sheet having its upper edge portion turned backwardly upon itself to form a retaining flange extending parallel to the remaining part of said sheet, vertical incisions provided in said flange at points corresponding to the corners in said wall, said counter-flashing being bent along vertical lines determined by said incisions to conform to the configuration of the wall and the flange of said counter-flashing being engaged over the upper edge of the wall portion of said reglet; and a plastic compound packed into the space between the wall and the engaged flange of said counter-flashing, said compound being banked up to form a slope slanting from said flange upwardly into contact with the face of the wall to which said reglet is secured.
